UNITED STATES PATENT OFFICE.

THOMAS DAVIS, OF DETROIT, MICHIGAN, ASSIGNOR TO THE JOHN FORD STARTER COMPANY, OF BALTIMORE, MARYLAND, A CORPORATION OF MARYLAND.

STARTER SYSTEM FOR AUTOMOBILES.

1,320,676.

Specification of Letters Patent.

Patented Nov. 4, 1919.

Application filed March 7, 1919. Serial No. 281,238.

To all whom it may concern:

Be it known that I, THOMAS DAVIS, a citizen of the United States, and resident of Detroit, Michigan, have invented certain new and useful Improvements in Starter Systems for Automobiles, of which the following is a specification:

In Letters Patent of the United States, No. 1,294,058, February 11th, 1919, granted 10 to me I show an air pressure system in connection with and forming a part of a starter apparatus for automobiles, in which when the starter valve is operated by the driver air under pressure is delivered to an air motor to drive the same and the motor by the air pressure is coupled up to the engine shaft to start the same, the air being restored in the system by a pump which is operated after the engine shaft is started and restores 15 pressure until it reaches the maximum when a controller will throw the pump out of operation.

My present invention relates to an apparatus of the above character, and it consists 20 in the features and combination and arrangement of parts hereinafter described and particularly pointed out in the claims.

In the drawings:

Figure 1 is a diagrammatic view of the 25 apparatus.

Fig. 2 is a sectional view of the air motor.

Fig. 3 is a longitudinal sectional view of the pump and associated parts.

Fig. 4 is a detail sectional view of the 30 pump valves.

In these drawings A is the compressed air tank which is connected by pipe a' with the starting motor A' and a pipe e^5 extends from the pump E to the tank to supply the 35 same with compressed air. This pump is arranged apart from the air motor and it is driven from the engine shaft n through sprockets n' , n^2 , and chain n^3 , instead of being driven from the engine shaft through 40 the shaft of the air motor, as in the patent referred to above, as will be referred to hereinafter more in detail.

In starting up with the tank A charged a 45 starter valve C is opened by the operator depressing the foot lever 14^x and air is admitted to the casing of the motor to drive the rotor thereof by acting on the blades, one of which is indicated at b . This rotor has a quill or hub c journaled in the 50 fixed casing or stator and this quill or hub

has a splined connection at g with a sleeve f which has fixed thereto a clutch member d . Within the sleeve there is a shaft e adapted to slide longitudinally and having a clutch member or members consisting of 60 the pins d' adapted to be engaged by the clutch d of the sleeve f when this sleeve is moved leftward from the position shown in Fig. 2 by the air pressure.

When the air is admitted to the air motor 65 to turn the same, together with its quill and sleeve f it is also admitted through the port h and channel j , to space k back of the clutch member d which therefore acts as a piston within the extension 4 of the rotor 70 casing and the axial movement of the clutch member d due to this air pressure causes it to engage the clutch pins d' and as the clutch member d is now in rotation with the rotor the shaft e will be turned, and 75 further this shaft will be moved axially toward the left, because of the axial movement of the sleeve f and its clutch d , due to the pressure of air at k .

This shaft has fixed rigidly thereto the 80 clutch member l and as the shaft is moved leftward the clutch l will engage a clutch member on the engine shaft n , consisting of the pin or pins m and thus the engine shaft will be started in rotation, and after the 85 engine shaft speeds up it will run ahead of the motor shaft e and release itself therefrom, the shaft e sliding to the right in this action. For this purpose the clutch l has inclines at l^x for the pins m to work against 90 in running ahead. Likewise the pins d' can run ahead of the clutch d because of the inclines at d^x on the jaws of the said clutch d . A spring e' bearing on a plate e'' resisting against the end of the quill c presses the 95 shaft e to normal position at the right of Fig. 2.

As above pointed out the pump is not operated from the engine shaft through the shaft e ; as in the patent above mentioned, 100 but is operated from the engine shaft, through a connection, which may be maintained after the engine shaft in the present case runs ahead of the shaft e , this connection being, as stated, the sprocket n' on the 105 engine shaft, the sprocket chain n^3 and the sprocket n^2 on the shaft e^2 of the pump.

The latter sprocket is not fixed to the shaft e^2 but as shown in Fig. 3 it is fixed to a sleeve n^x loose on the shaft, but held 110

against axial displacement by its flanged end running in a groove n^4 of the pump casing. The shaft e^2 is slidable axially and it has a clutch member d^2 to engage the clutch 5 face d^3 of the sprocket n^2 . The slidable pump shaft carries splined thereto an eccentric E' for operating the piston rod and piston E^2 for compressing air, suitable intake and outlet valves being shown at e^5 , e^6 , 10 Fig. 4.

The pump shaft is pressed to the right to make its clutch d^2 connect with the clutch face of the sprocket by a spring 8, this condition existing when the air pressure in the 15 system is reduced and the pump is to work to restore the pressure. When the pressure is restored to the maximum the shaft e^2 is slid leftward to disengage the clutch at d^2 , d^3 , by means of a lever 9 pivoted to 20 a bracket at 10 and operated from a diaphragm O through a pin or plunger 12. The diaphragm is subjected to the pressure in the system because its casing is connected with the pipe 6 leading from a controller 25 D which performs the general functions of the controller shown in said patent at D, though the controller herein represented is like that described in an application executed by me of even date herewith. When 30 the pressure rises to the maximum for which the controller is set air pressure is delivered by the controller from the tank to the pipe 6 and to the diaphragm O which will, through the lever 9, slide the pump shaft 35 longitudinally to disconnect it from the engine shaft by throwing out the clutch d^2 , and thus stop the pump.

The controller is connected with the pipe a' and tank by a pipe 5. 40 When the air pressure falls to the minimum point for which the controller is set the air is let out of pipe 6, the diaphragm collapses and the spring 8 throws the clutch d^2 , d^3 in and the pump is operated by the 45 engine to restore the pressure and this may occur in case of leakage, or when the engine is started.

It is desirable in starting the engine that the pump be disconnected so that the additional load on the engine, which a connected 50 pump would entail, will be avoided. I therefore employ a piston 13 in a cylinder 14 which is connected by a pipe 15 with the air pipe a' , so that when the starter 55 valve C is opened the air pressure will move the piston 13 leftward and through its piston rod will move the lever 9 to slide the pump shaft leftward and throw out its clutch d^2 , thus cutting off the pump from 60 the engine and therefore reducing the load on the engine, which otherwise would exist if the pump were driven by the engine in starting.

This condition will prevail as long as 65 the starter valve remains open and the pres-

sure on the piston through pipe 15 is sufficient to overcome the pressure of the spring 8, but after the engine is well started the pressure of the air in the tank and system will have become reduced and the spring 70 8 will then act to overcome the pressure back of piston 13 and will throw in the clutch d^3 to operate the pump from the engine shaft. The diaphragm O will not oppose this action because, as above pointed out the diaphragm will be collapsed when the air pressure is lowered to a certain point. 75

A choke is provided at 7 in the pipe a' which acts in a manner similar to that disclosed in the patent mentioned.

It causes the governor D to be affected by a quick reduction of pressure, each time the starter valve C is opened to admit air to the motor, resulting in opening the pipe 6 to atmosphere through the atmospheric port 22 and the collapsing of the diaphragm O .

The clutch d , d' between the sleeve f of the rotor and the motor shaft e is to enable hand cranking to be done with the motor idle. The operator places the crank on the end of the shaft e and first pushes the shaft to the left and then spins it. The leftward movement of the shaft sets the clutch at l into connection with the engine shaft 95 and also disconnects the motor at the clutch d , d' so that in hand cranking the resistance of the motor does not have to be overcome, it remaining at rest.

When the piston is operated by pressure back of it this pressure will leak or bleed out as soon as the starter valve is closed and thus the spring 8 may quickly move the shaft e^2 to the right to couple with the engine through the clutch d^2 . This leakage may take place through the parts of the starter valve or a special bleed port may be used.

One purpose of the spring for returning the shaft e to the right is to draw washer x against the end of the small cylinder 4 to exclude dust. So far as the detaching of the shaft e from the engine shaft is concerned, this is done by the engine shaft running ahead. The spring aids in holding the shaft in its detached position.

What I claim is:

1. In combination an engine shaft, a compressed air reservoir, a starting motor comprising a rotor and a casing therefor, a shaft slidable axially through the rotor, connecting means between the rotor and the slidable shaft to allow the shaft to slide relative to the rotor, means for supplying air pressure for turning the rotor and for sliding said shaft, a clutch between the slidable shaft and the engine shaft allowing the engine shaft to run ahead of the motor shaft, a pump and pump shaft, a clutch between the engine shaft and the pump shaft and

means operated by the air pressure for controlling said clutch, substantially as described.

2. In combination, an engine shaft, a compressed air reservoir, a starting motor comprising a rotor and a casing therefor, a shaft slidably axially through the rotor, connecting means between the rotor and the slidable shaft to allow the shaft to slide relative to the rotor, a clutch between the slidable shaft and the engine shaft, a pump and pump shaft, a clutch between the engine shaft and the pump shaft and means operated by the air pressure for controlling said clutch, substantially as described.

3. In combination with an engine shaft, an air motor comprising a casing and a rotor having only rotary movement therein, a rotor shaft, means for driving the rotor by air pressure, means for sliding the rotor shaft by air pressure in relation to the rotor, said rotor shaft and rotor having a sliding connection between them, which will permit the shaft to slide and also cause the shaft to be rotated by the rotor, a clutch between the slidable rotor shaft and the engine shaft, said clutch having inclines by which the engine shaft can run ahead of the rotor shaft, and a spring for sliding the rotor shaft to normal unclutched position, substantially as described.

4. In combination an engine and its shaft, an air motor with pneumatically operated clutch means for connecting the motor with the engine and adapted to allow the engine to unclutch and run ahead of the motor, a spring for assisting in restoring the clutch to normal position, a pump, a clutch between the same and the engine shaft, and a pneumatically operated means for throwing the pump clutch into operation when the air pressure in the system is reduced and for throwing the pump clutch out of operation when the air pressure reaches a maximum, substantially as described.

5. In combination an engine shaft, an air motor for starting the same, an air reservoir, a pipe connection between the same and the motor clutch means whereby the pump is driven from the engine, and pneumatically operating means for throwing said clutch out of operation to disconnect the pump from the engine while the engine is starting and for throwing the clutch in to operate the pump after the engine is running to thereby restore air into the system, substantially as described.

6. In combination an engine shaft, an air motor for starting the same, an air reservoir, a pipe connection between the same and the motor clutch means whereby the pump is driven from the engine, and pneumatically operating means for throwing said clutch out of operation to disconnect the pump from the engine while the engine is starting

and for throwing the clutch in to operate the pump after the engine is running to thereby restore air into the system, and pneumatically operating means for throwing the clutch out when the pressure is restored in the system, substantially as described.

7. In a compressed air starting system for automobiles and the like and in combination with the engine and its shaft, a compressed air motor for starting the engine shaft, a pump for restoring pressure to the system, automatically operating means for throwing the pump out of operation and then into operation including pneumatic means disconnecting the pump from its operating connection when starting, and pneumatic means for throwing the pump out of operation again when the pressure has been raised to the desired point, substantially as described.

8. In a compressed air starting system for automobiles the combination of an engine and its shaft, an air motor for driving the shaft, a pump, a clutch between the pump and the engine shaft, a pneumatic device for throwing the clutch out of operation when the engine is started, a spring for throwing the clutch into operation after the pressure is reduced consequent upon its use in starting the engine, and a second pneumatic device receiving the air pressure of the system and acting in opposition to the spring to throw the clutch out of operation when the pressure reaches a predetermined maximum, substantially as described.

9. In a compressed air starting system for automobiles, and in combination with an engine and its shaft, a starting air motor with its shaft arranged coaxially with the engine shaft, clutch means between the said shafts, a pump arranged with its shaft parallel with the engine shaft, a driving connection between the engine shaft and the pump shaft including a clutch, pneumatically operated means for throwing the first clutch in to start the engine from the air motor and pneumatic means for throwing the pump clutch out, both of said means performing the stated acts when the pressure rises against them, substantially as described.

10. In a compressed air starting system for automobiles, and in combination with an engine and its shaft, a starting air motor with its shaft arranged coaxially with the engine shaft, clutch means between the said shafts, a pump arranged with its shaft parallel with the engine shaft, a driving connection between the engine shaft and the pump shaft including a clutch, pneumatically operated means for throwing the first clutch in to start the engine from the air motor and pneumatic means for throwing the pump clutch out, both of said means per-

forming the stated acts when the pressure rises against them, and a spring for each clutch means acting in opposition to the pneumatic means, substantially as described.

5 11. In a compressed air starting system for automobiles and in combination, an engine and its shaft, an air motor having a 10 slidable shaft with a clutch between the same and the engine shaft to be thrown in and out by sliding said shaft, a pump having an axially slidable shaft, a clutch drive between the engine shaft and the pump shaft, which is released and set by sliding said pump shaft, pneumatic means for sliding the motor shaft and pneumatic means for sliding the pump shaft, substantially as described.

10 12. In a compressed air starting system for automobiles and in combination, an engine and its shaft, an air motor having a 15 slidable shaft with a clutch between the same and the engine shaft to be thrown in and out by sliding said shaft, a pump having an axially slidable shaft, a clutch drive between the engine shaft and the pump shaft, which is released and set by sliding said pump shaft, pneumatic means for sliding the motor shaft and pneumatic means for sliding the pump shaft, said motor shaft 20 being slid to clutch and said pump shaft to unclutch by their respective pneumatic means and springs for operating the shafts in the direction opposite from the direction of operation by the pneumatic means belonging thereto, substantially as described.

25 13. In a compressed air system for starting automobiles, and in combination with an engine and its shaft, an air motor for starting the engine, a pump for restoring air to the system, said pump having an axially slidable shaft, a member for driving the shaft, a clutch for connecting said member with the shaft, said clutch being set or released by sliding the shaft one way and then the other, means for sliding the shaft to throw out the clutch operated pneumatically, and a spring for sliding the shaft in the opposite direction, substantially as described.

30 14. In an engine starter and in combination with the pump and its axially slidable shaft, a clutch operated by the sliding of said shaft, a device operated by the starting air pressure for moving the shaft to disconnect its clutch after which the clutch is thrown in and a second device operated by the air on reaching its maximum pressure to operate said shaft to again disconnect the clutch, substantially as described.

35 15. In an engine starter and in combination with the pump and its axially slidable shaft, a clutch operated by the sliding of said shaft, a device operated by the starting air pressure for moving the shaft to disconnect its clutch after which the clutch is thrown

in and a second device operated by the air on reaching its maximum pressure to operate said shaft to again disconnect the clutch, said devices acting through a lever common to them both, substantially as described.

40 16. In a starter system for automobile engines, and in combination with an engine shaft, an air motor, a clutch between the same and the engine shaft, a pump, a connection between the same and the engine shaft including a clutch, means for throwing the first mentioned clutch in to start the engine shaft, said means operating by air pressure, means for throwing the last 45 mentioned clutch out operating by air pressure when this reaches a maximum, means for throwing the latter clutch in on reduction of the air pressure, and means whereby the first clutch is thrown out when the engine has been started, substantially as described.

50 17. In a starter system for automobile engines, and in combination with an engine shaft, an air motor, a clutch between the same and the engine shaft, a pump, a connection between the same and the engine shaft including a clutch, means for throwing the first mentioned clutch in to start the engine shaft, said means operating by air 55 pressure, means for throwing the last mentioned clutch out operating by air pressure when this reaches a maximum, means for throwing the latter clutch in on reduction of the air pressure, and means whereby the first clutch is thrown out when the engine has been started, and means for throwing out the pump clutch when the engine is being started to relieve it of the load of the pump during the starting, said clutch being 60 thrown in after the engine is running, to operate the pump for restoring air into the system, substantially as described.

55 18. In combination in a starter apparatus for automobile engines, an air motor, means for clutching the same to the engine shaft, said means unclutching automatically when the engine picks up, a pump, clutch means for operating the same from the engine shaft, including a pneumatic device for 65 holding the said clutch out when the engine is starting to keep load off of the engine and for throwing said clutch in after the engine has started to thereby restore air pressure in the system and means operated pneumatically for throwing said clutch out when the air pressure is restored, substantially as described.

70 19. In combination in a compressed air 75 starter for automobiles, an air motor having a shaft slidably axially in relation thereto, a clutch between said shaft and the engine shaft, which will allow the engine shaft to run ahead of the motor shaft, means for 80 sliding the shaft to set the clutch when air 85

is supplied to the motor; a pump and pump shaft and a connection including a clutch for driving the pump from the engine shaft and means operated by air pressure in the system and controlling the clutch last mentioned, substantially as described.

20. In combination in a compressed air starter for automobiles, an air motor having a shaft slidable axially in relation thereto, a clutch between said shaft and the engine shaft which will allow the engine shaft to run ahead of the motor shaft, means for sliding the shaft by the pressure of air, to set the clutch when air is supplied to the motor, a pump and pump shaft and a connection including a clutch for driving the pump from the engine shaft and means operated by air pressure in the system and controlling the clutch last mentioned.

20 21. In combination in a compressed air starter for automobiles, an air motor having a shaft slidable axially in relation thereto, a clutch between said shaft and the engine shaft which will allow the engine shaft to run ahead of the motor shaft, means for sliding the shaft to set the clutch when air is supplied to the motor, a pump and pump shaft and a connection including a clutch for driving the pump from the engine shaft, and automatic means for eliminating the pump when the engine is starting, substantially as described.

22. In combination in a compressed air starter for automobiles, an air motor having a shaft slidable axially in relation to said motor, a clutch between said shaft and the engine which will allow the engine shaft to run ahead of the motor shaft, means for sliding the shaft to set the clutch when air is supplied to the motor, a pump and pump shaft and a connection including a clutch for driving the pump from the engine shaft, and means for automatically eliminating the pump when the engine is starting and automatically restoring the action of the pump after the engine is started and automatic means for eliminating the pump when the pressure in the tank reaches a certain maximum, substantially as described.

50 23. In combination in a compressed air starter for automobiles, an air motor having a shaft slidable axially, a clutch between said shaft and the engine shaft which will allow the engine shaft to run ahead of the motor shaft, means for sliding the shaft to set the clutch when air is supplied to the

motor, a pump and pump shaft and a connection including a clutch for driving the pump from the engine shaft, the said motor shaft being slid, to connect with the engine by air pressure, air pressure operated means to eliminate the pump when the engine is started, and air pressure operated means for eliminating the pump when the pressure reaches a predetermined maximum, substantially as described.

24. In a starter system for automobile engines the combination with the engine shaft, a motor, a motor shaft, slidable axially of the motor, a clutch between the motor shaft and engine shaft adapted to allow the engine shaft to run ahead of the motor shaft, said motor shaft having its end adapted to receive a crank for hand cranking the car, a clutch member on the motor shaft, a sleeve splined to the motor hub and having a clutch member to engage the clutch member of the motor shaft, the said members being detached when the shaft is slid by hand cranking into connection with the engine shaft. 80

25. In a starter system for automobiles the combination with the engine shaft, a motor, a motor shaft, slidable axially of the motor, a clutch between the motor shaft and engine shaft to run ahead of the motor shaft, said motor shaft having its end adapted to receive a crank for hand cranking the car, a clutch member on the motor shaft, a sleeve splined to the motor hub and having a clutch member to engage the clutch member of the motor shaft, the said members being detached when the shaft is slid by hand cranking into connection with the engine shaft, and means for directing air back of the clutch member of the sleeve to slide the shaft 95 to make all clutch members engage, substantially as described.

26. In combination with the shaft of an automobile engine a starting air motor having a shaft with clutch means between it and the engine shaft which will allow the engine shaft to run ahead of the motor shaft, a tank for compressed air to be supplied to the motor, a pump for compressing air into the system and pneumatically controlled means for initially disconnecting the pump when the engine is started and for thereafter bringing the pump into connection with the engine shaft to be driven thereby. 100

In testimony whereof, I affix my signature. 110

THOMAS DAVIS.
